TOE-LASTING MACHINE

Bernhardt Jorgensen, Marblehead, Mass., assignor to United Shoe Machinery Corporation, Flemington, N. J., a corporation of New Jersey

Application March 11, 1944, Serial No. 526,015

18 Claims. (Cl. 12—14)

This invention relates to machines for lasting the toe ends of shoes. The invention is herein illustrated as embodied in a modification of a machine constructed generally as disclosed in United States Letters Patent No. 2,324,509, granted on July 20, 1943, on an application of mine, but it is to be understood that it is not thus limited in its applicability.

The machine shown in the above-mentioned Letters Patent is provided with means for trimming the margin of one or more inner layers of the toe-end portion of a multi-ply upper on a last while leaving a margin of the outer layer to be lasted inwardly over an insole on the last. The machine also includes a plurality of grippers which grip the margin of the several layers of the upper about the toe and pull the upper outwardly in directions lengthwise and widthwise of the last, and a toe former which embraces the upper about the toe and is moved lengthwise of the last to wipe the upper into conformity to the contour of the toe end of the last while it is held by the grippers preparatory to the upper-trimming operation. Associated with the toe former are wipers which are movable with it heightwise of the last and are also movable to wipe the margin of the outer layer of the upper inwardly over the insole after the upper-trimming operation. Prior to such overwiping movements of the wipers a cement-applying device is moved heightwise of the last into engagement with the toe end of the insole and applies cement thereto for securing the margin of the upper to the insole when it is wiped inwardly by the wipers. Movable into operative position with the cement-applying device is another device which clamps the margin of the outer layer of the upper outspread on the wipers and serves as a retarder to assist the wipers in wiping the upper smoothly and tightly over the insole. In the course of the overwiping operation, moreover, the cement-applying device is forced away from the insole by the inward movements of the wipers and serves as an additional retarder to control the margin of the upper.

In accordance with the further disclosure of Letters Patent No. 2,337,558, granted on December 28, 1943, on an application of mine, the above-mentioned machine was modified in such manner as to cause the grippers again to grip the margin of the upper after the upper-trimming operation and to apply a pull to the outer layer only of the upper in order to stretch and shape it more effectively. Prior to this second pull of the grippers the toe former and the

wipers were withdrawn from the shoe, and they were again moved heightwise of the last to cause the toe former to wipe the upper a second time in that direction toward the edge of the insole while the outer layer of the upper was held under tension by the grippers. Thereafter the grippers were opened to release the upper as the wipers began to wipe its margin inwardly over the insole. In order to permit such use of the grippers, the retarder above referred to as associated with the cement-applying device in the construction shown in the first-mentioned Letters Patent was omitted.

The present invention provides a construction whereby the advantages of such a second pull on the outer layer of the upper after the upper-trimming operation are obtained without the use of the grippers for that purpose. As in the construction shown in Letters Patent No. 2,337,558, the toe former and the wipers are withdrawn from the shoe after the upper-trimming operation, the grippers having released the margin of the upper, and are then moved heightwise of the last to cause the toe former to wipe the upper a second time in that direction and to bring the wipers to the proper plane for wiping the margin of the upper inwardly over the insole. For applying the second pull to the outer layer of the upper there is provided a retarder which clamps the margin of the outer layer outspread on the wipers before the toe former and the wipers complete their second movement heightwise of the last and cooperates with the wipers during the completion of that movement to pull the upper. As illustrated, this retarder is associated with the cement-applying device, similarly to the retarder shown in Letters Patent No. 2,324,509, but is differently arranged in relation thereto for the purposes in view. In accordance with one feature of the invention, moreover, novel mechanism is provided for controlling the retarder in such manner as to cause it to move outwardly over the wipers with a wiping action on the margin of the upper to insure that the margin will be smoothly outspread on the wipers. As illustrated, this mechanism comprises parallel links which support the retarder and impart the outward wiping movement thereto in response to the movement of the wipers heightwise of the last. For better results in operating on some kinds of upper materials, both the retarder and the cement-applying device, which is arranged to serve as an additional retarder as hereinabove explained, may be withdrawn from the shoe heightwise thereof to release the upper early in

the inward wiping movements of the wipers, as further herein illustrated, to provide for less strain on the upper in the overwiping operation.

The above and other features of the invention, including various novel details of construction and combinations of parts, will now be more particularly described with reference to the accompanying drawings and thereafter pointed out in the claims.

In the drawings,

Fig. 1 is a view, mainly in left-hand side elevation, of the upper portion of the machine in which the invention is herein illustrated as embodied;

Fig. 2 is a vertical sectional view showing the toe end of a shoe and the parts closely associated therewith as they appear shortly after the upper has been pulled by the grippers and while it is held under tension;

Fig. 3 is a similar view with the parts positioned as they are immediately prior to the upper-trimming operation;

Fig. 4 is mainly a plan view showing the parts as they appear at the same time in the operation of the machine as in Fig. 3;

Fig. 5 is a view similar to Fig. 2, illustrating the positions of the parts at a certain time in the upper-trimming operation;

Fig. 6 shows the toe former and the wipers withdrawn from the shoe after the upper-trimming operation preparatory to the second upwiping movement of the toe former;

Fig. 7 is a view similar to Fig. 6, but showing the cement-applying device in engagement with the insole and the retarder in position for clamping the outspread margin of the outer layer of the trimmed upper on the wipers when the wipers are next moved upward with the toe former;

Fig. 8 shows the positions of the parts prior to the completion of the second upwiping movement of the toe former after the margin of the outer layer of the upper has been clamped on the wipers by the retarder;

Fig. 9 is a view partly in plan and partly in section on the line IX--IX of Fig. 8 with the parts positioned as in Fig. 8;

Fig. 10 shows the parts as they appear just after the wipers begin their movements to wipe the margin of the outer layer of the upper inwardly over the insole;

Fig. 11 shows the wipers in the course of their overwiping movements, the cement-applying device and the retarder having been lifted;

Fig. 12 shows the wipers as they appear at the end of their overwiping movements; and

Fig. 13 is a chart illustrating the timing of the various operations performed in the cycle of operations of the machine.

In view of the disclosures in the above-mentioned Letters Patent, only such parts of the machine as it is necessary to refer to for an understanding of the invention will be hereinafter particularly described. It will be understood that the machine is a fluid-operated machine in which various mechanisms are operated in predetermined time relation to one another by fluid admitted to cylinder-and-piston devices associated respectively with the different mechanisms, the admission of the fluid and its release from the cylinder-and-piston devices being effected by valves which are controlled by automatically acting fingers like the fingers 354, 356 shown in Letters Patent No. 2,337,558.

While any suitable means may be used for

positioning the shoe in proper relation to the instrumentalities which operate thereon, the machine herein shown is provided for this purpose, as heretofore, with a plate 2 arranged to be engaged by the bottom face of the toe end of the insole and with a plurality of pins 4 arranged to extend through holes in the insole into holes in the last. Substantially at the beginning of the power operation of the machine the shoe is clamped against the plate 2 by a toe rest 6 and an instep support 8. To assist in holding the shoe against lengthwise displacement there is also provided a heel rest 10 (Figs. 1 and 3) movable into engagement with the heel-end face of the shoe.

When the operator presents the shoe in the position determined by the plate 2 and the pins 4 he positions the margin of the several layers of the toe-end portion of the upper outspread between the jaws of a toe-end gripper 12 and side grippers 14 (Fig. 4), and shortly after the beginning of the power operation of the machine these grippers are operated to pull the upper, the toe-end gripper being moved lengthwise of the last and the side grippers widthwise of the last. All three grippers, moreover, receive a comparatively short upward movement. After the pulling of the upper and while it is held under strain by the grippers a substantially U-shaped flexible toe former 16 is moved upwardly to wipe the toe-end portion of the upper heightwise of the last to the edge of the insole and to conform it to the contour of the last, and in this operation the grippers may be moved somewhat inwardly toward the last by the pull of the upper thereon against the resistance of springs (not shown) which control them. Immediately above the toe former 16 are wipers 18 for wiping the margin of the upper inwardly over the insole, these wipers being movable upwardly with the toe former to positions where they engage and support the outspread margin of the upper held by the grippers. For the purpose of such upward movement of the toe former and the wipers as a unit they are carried by a common support 20 (Fig. 1) mounted for upward and downward movements on parallel links 22 and 24.

After the upper has thus been wiped heightwise of the last by the toe former, its outspread margin is trimmed to remove therefrom all but the outer layer of the upper materials. For this purpose the machine is provided with upper-trimming mechanism 26 (Fig. 1) mounted on a carrier 28 which is movable downwardly to bring the mechanism into proper position for operating on the upper. The upper-trimming mechanism includes a pair of side-trimming knives 30 (Figs. 1 and 4) mounted to swing outward laterally of the shoe toward the side grippers 14 from positions over the bottom of the shoe, and a middle knife 32 movable rectilinearly lengthwise of the shoe in an outward direction toward the end gripper 12 to complete the upper-trimming operation after the movements of the side knives. The middle knife 32 is supported on an arm 34 which is swung downwardly to carry the knife to the proper plane for operating on the upper and is movable bodily to cause the knife to perform the trimming operation. The three knives, in operating on the upper, move in a plane parallel to the top faces of the wipers 18, and in proper time relation to the movements of the knives the grippers are opened to release the upper and are then moved farther outwardly by their con-

trolling springs to prevent interference with the knives.

Also supported on the carrier 28, as heretofore, is a cement-applying device 36 (Fig. 7) by which cement is applied to the toe end of the insole for securing the margin of the outer layer of the upper to the insole. This device includes a cement receptacle 38, an insole-engaging member 40 (Figs. 7 and 9) having a plurality of openings through which cement is delivered from the receptacle, and an automatically acting pump plunger 42 for delivering the cement. The cement-applying device is carried to a position over the toe end of the shoe by swinging movement of the carrier 28 about a vertical axis after the carrier has been moved upwardly to withdraw the upper-trimming mechanism 26 from the shoe, and the carrier is then moved downwardly to carry the member 40 of the cement-applying device into engagement with the insole, as illustrated in Fig. 7, the cement being delivered near the end of the downward movement of the device. The cement-applying device is supported directly on parallel links 44 and 46 mounted respectively on rods 48 and 50 on the carrier 28, thus permitting relative upward or downward movement of the device and the carrier. Spring means not herein shown but disclosed in Letters Patent No. 2,324,509 serves in addition to gravity to maintain the cement-applying device normally at a predetermined limit of downward movement relatively to the carrier 28 and permits such slight further downward movement of the carrier as occurs after the member 40 of the cement-applying device has engaged the insole. The member 40 is provided with an inclined face 52 against which the margin of the upper is pressed by the wipers 18, and by this pressure the cement-applying device is forced upwardly away from the insole as the wipers wipe the margin of the upper inwardly, the member 40 thus acting as a retarder to render the wipers more effective to wipe the upper tightly and smoothly over the insole.

After the upper-trimming operation the toe former 16 and the wipers 18 are retracted as a unit from the shoe lengthwise thereof and are moved downwardly, as illustrated in Fig. 6, preparatory to a second upward movement to cause the toe former again to wipe the upper heightwise of the last, the machine herein shown operating in this respect like that disclosed in Letters Patent No. 2,337,558. As distinguished, however, from that prior disclosure, the grippers 12 and 14 remain idle after their first pull on the upper materials and do not apply a second pull to the outer layer of the upper. Instead of using the grippers for this purpose, the machine is provided with a retarder 54 which is moved downwardly with the cement-applying device 36 and thereby assumes a position for clamping the outspread margin of the outer layer of the upper on the top faces of the wipers in a plane below the edge of the insole when the wipers have been moved upwardly with the toe former far enough to cause such clamping action to occur. Thereafter, during further upward movement of the wipers with the toe former, the retarder and the wipers cooperate to apply a pull to the outer layer of the upper.

The retarder 54 is constructed substantially like that disclosed in Letters Patent No. 2,324,509. It comprises a pair of plates 56 (Fig. 9) curved at their inner edges similarly to the edges of the wipers 18 and provided with downwardly extend-

ing curved flanges 58 for clamping engagement with the upper near the wiping edges of the wipers. The plates 56 are provided respectively with upwardly extending tubular portions 60 and 62, one mounted within the other and the inner one mounted on a cylindrical stem 64 on the lower end of a bar 66. The two plates may be adjusted relatively to each other about the axis of the stem, and they are held in adjusted positions by a split collar 68 (Fig. 7) which extends around the outer tubular portion 60 and is contracted by a screw 70, both the tubular portions being split part way downward from their upper ends. The bar 66 is shaped somewhat differently than the corresponding part shown in Letters Patent No. 2,324,509, and it is supported by pins 72 and 74 on a pair of comparatively short parallel links 76 and 78 which are pivotally mounted respectively on pins 80 and 82 in a hollow casing 84. This casing, one wall of which is partly broken away in Fig. 7, is mounted on the two rods 48 and 50 which support the links 44 and 46. The casing 84 is provided with vertical slots 86 and 88 through which respectively the rods 48 and 50 extend, and these slots permit the casing to be vertically adjusted relatively to the carrier 28 to vary the initial position of the retarder 54 heightwise of the shoe relatively to the position of the insole-engaging member 40 of the cement-applying device. For the purpose of such adjustment there is threaded in the casing 84 a screw 90 which engages the rod 50 underneath and there is further mounted in the casing a spring 92 which presses downwardly on a plunger 94 engaging the top of the rod 50. It will be understood that the spring 92 is strong enough to lift the casing and the parts supported thereon, so that the screw 90 is held at all times against the rod 50 and is accordingly effective to vary the position of the casing.

A spring 96 connected to an ear 98 on the link 76 tends in addition to gravity to move the retarder 54 in a downward direction, the limit of its downward movement relatively to the casing 84 being determined by engagement of one side of the bar 66 with the pin 82. When the retarder 54 is forced upwardly by the wipers in the course of the second upwiping movement of the toe former 16 the spring 96 is tensioned while holding the retarder yieldingly against the margin of the upper. The force with which the retarder thus engages the upper may be varied by adjusting the tension of the spring. For this purpose there is provided an arm 100 connected to the lower end of the spring and fastened to a shaft 102 which is mounted to turn in the casing 84. Also fast on one end of this shaft is an arm 104 provided with a knob 106 for swinging it to adjust the tension of the spring. The arm 104 is resiliently flexible in directions widthwise of the casing 84 and carries a pin 108 arranged to enter any one of a plurality of holes 110 in one wall of the casing. By springing the arm 104 in an outward direction the pin may be withdrawn from any of the holes.

It will be observed that the links 76 and 78 are not only short but are also steeply inclined in such manner that in response to the upward movement of the wipers the retarder, as it is lifted, is moved outwardly over the wipers in a direction away from the toe end of the shoe while maintained by the links in parallel relation to the wipers. The retarder, therefore, has an outward wiping action on the outspread margin of the upper, which affords better insurance that

the margin of the upper will be smoothly clamped on the wipers.

By reference to Fig. 10 it will be seen that just after the wipers begin to wipe the margin of the upper inwardly over the insole the upper, still controlled by the retarder 54, is pressed against the inclined face of the insole-engaging member 40 of the cement-applying device 36. By this pressure the member 40 is forced upwardly away from the insole while also acting as a retarder, as hereinbefore explained. Under some conditions, as when the upper stock is of comparatively light weight, it may be desirable to release the margin of the upper from the pressure of both the member 40 and the retarder 54 early in the inward movements of the wipers, thus avoiding excessive strain on the upper as its margin is wiped inwardly. This may be done, for example, immediately after the wipers arrive in the positions of Fig. 10, the member 40 and the retarder 54 being lifted as illustrated in Fig. 11 by upward movement of the carrier 28. This carrier is moved downwardly to carry the upper-trimming mechanism 26, and thereafter the cement-applying device 36, toward the shoe by fluid admitted into the upper end of a cylinder 112 (Fig. 1), the fluid acting on a piston 114 to which the carrier 28 is secured; and upward movement of the carrier is effected at the required times by a spring 116 acting on the piston 114 when fluid is released from the cylinder 112. To cause the carrier to be moved upward precisely at the time required to release the margin of the upper as above described, it is only necessary properly to adjust the automatic means whereby fluid is released from the cylinder 112.

The manner of operation of the machine, in so far as it is of interest for an understanding of the present invention, will now be briefly summarized with reference particularly to the chart (Fig. 13) which shows the preferable timing of the various operations. On this chart, as on a similar chart in Letters Patent No. 2,337,558, the double lines indicate the times when the operating fluid is effective to operate the parts or to perform the operations designated, or to maintain the parts in positions to which they have been moved, and the single lines indicate the times when the pressure of the fluid thus acting is relieved. A comparison of the present chart with that in the above-mentioned Letters Patent will show, as far as the timing of the valves is concerned, the changes that have been made in the cycle of operations for purposes of this invention, these changes resulting from omission of some of the previously mentioned valve-controlling fingers and from adjustment or rearrangement of others of the fingers.

When the operator presents the shoe to the machine in the position determined by the plate 2 and the pins 4 he positions the margin of the several layers of the toe-end portion of the upper outspread between the jaws of the grippers 12 and 14, and prior to the starting of the cycle of operations of the machine the grippers are closed, as heretofore, on the several layers. Immediately after the starting of the cycle the toe rest 6, the instep support 8 and the heel rest 10 are moved into their operative positions, and shortly thereafter the grippers are operated to pull the toe end of the upper lengthwise and laterally, as illustrated in Figs. 2 and 4. While the grippers are holding the upper under tension the carrier 28 which supports the upper-trimming mechanism 26 and the cement-applying device

36 is moved downwardly to carry the upper-trimming mechanism into position to operate on the shoe, and upward movement is imparted to the support 20 to raise the toe former 16 and the wipers 18 and thus to cause the toe former to wipe the toe end of the upper toward the edge of the insole into conformity to the contour of the toe end of the last, as illustrated in Fig. 3. The next operation performed is the trimming of the upper by the movements of the trimming knives 30 and 32, the action of the middle knife 32 on the upper being illustrated in Fig. 5. In time relation to the movements of the trimming knives the grippers are opened to release the upper and are retracted from the paths of movement of the knives by the springs which control them, the grippers being thereafter held in retracted positions until near the end of the cycle by maintaining the fluid pressure in the devices whereby they are operated. It will be understood that by the action of the trimming knives, moving in a plane parallel to the wipers 18 over the marginal portion of the upper materials supported on the top faces of the wipers, the margin of all but the outer layer of the toe-end portion of the upper is trimmed off, leaving the margin of the outer layer to be lasted thereafter inwardly over the insole next to the insole. While the drawings, for convenience, show only a single layer of upper materials in addition to the outer layer, it will be understood that the toe-end portion of the upper will usually comprise at least three layers of materials. After the trimming operation the carrier 28 is raised to withdraw the trimming mechanism from the vicinity of the shoe and the trimming knives are returned to their starting positions on the carrier.

Shortly after the trimming of the upper the wipers and the toe former are retracted from the shoe lengthwise thereof and are released for downward movement by gravity, as illustrated in Fig. 6. Thereafter, the carrier 28 is swung to carry the cement-applying device 36 to a position over the toe end of the shoe and is moved downwardly to carry this device into engagement with the toe end of the insole and to apply cement to the insole, as shown in Fig. 7. Movable downwardly with the cement-applying device is the retarder 54 the upper-engaging flanges 58 of which deflect the outturned margin of the outer layer of the upper downwardly beyond the edge of the insole, as also illustrated in Fig. 7. Shortly thereafter the wipers and the toe former are moved reversely lengthwise of the shoe and are raised to cause the toe former again to conform the toe end of the upper to the contour of the last. Again the wipers in their upward movement opposite the toe-end face of the last with the toe former arrive in positions to clamp the outturned margin of the outer layer of the upper against the retarder 54 in a plane below the edge of the insole, the wipers and the retarder cooperate during further upward movement of the wipers to apply a pull to the outer layer only of the upper materials, as illustrated progressively by Figs. 8 and 10. As upward movement is imparted to the retarder by the wipers against the resistance of the spring 96, the links 76 and 78 which support the retarder are swung toward horizontal positions and thereby impart to the retarder an outward movement lengthwise of the shoe over the wipers. The retarder by its outward wiping action on the margin of the upper thus insures that the margin will be clamped smoothly on the wipers. After the upward move-

ment of the toe former and the wipers, movements are imparted to the wipers to wipe the margin of the outer layer of the upper inwardly over the insole. Just after the wipers begin to wipe the margin of the upper inwardly over the insole the upper, which is still controlled by the retarder 54, is pressed by the wipers against the inclined face of the insole-engaging member 40 of the cement-applying device 36, and in response to this pressure the member 40 begins to move upwardly away from the insole while acting as an additional retarder, as illustrated in Fig. 10. Immediately thereafter the carrier 28 is moved upwardly to cause the member 40 and the retarder 54 to release the margin of the upper (Fig. 11), thus avoiding excessive strain on the upper in operating on some kinds of upper materials. By their continued movements the wipers then wipe the margin of the upper throughout its width over the insole, as shown in Fig. 12. The remainder of the cycle of operations need not be described, since it is substantially the same as disclosed in Letters Patent No. 2,337,558.

Having described the invention, what I claim as new and desire to secure by Letters Patent of the United States is:

1. In a toe-lasting machine, means for trimming the margin of one or more inner layers of the toe-end portion of a multi-ply upper on a last while leaving a margin of the outer layer to be lasted over an insole on the last next to the insole, wipers for wiping the margin of the outer layer inwardly over the insole after the upper-trimming operation, and means arranged to clamp the margin of the outer layer of the upper on the wipers in a plane between the edge of the insole and the top of the toe end of the last after the upper-trimming operation and to cooperate with the wipers to apply a pull heightwise of the last to that layer only prior to the wiping of its margin inwardly over the insole.

2. In a toe-lasting machine, means for trimming the margin of one or more inner layers of the toe-end portion of a multi-ply upper on a last while leaving a margin of the outer layer to be lasted over an insole on the last next to the insole, wipers for wiping the margin of the outer layer inwardly over the insole, a toe former for wiping the toe end of the upper heightwise of the last after the upper-trimming operation, and means arranged to clamp the margin of the outer layer of the upper on the wipers and to cooperate with them to apply a pull heightwise of the last to that layer only as the upper is wiped heightwise of the last by the toe former.

3. In a toe-lasting machine, means for trimming the margin of one or more inner layers of the toe-end portion of a multi-ply upper on a last while leaving a margin of the outer layer to be lasted over an insole on the last next to the insole, wipers for wiping the margin of the outer layer inwardly over the insole after the upper-trimming operation, said wipers being movable heightwise of the last opposite its toe-end face into position for thus wiping the upper inwardly, and means arranged to clamp the margin of the outer layer of the upper on the wipers in a location spaced heightwise of the last from the edge of the insole after the upper-trimming operation and to cooperate with the wipers to apply a pull to that layer only as the wipers are thus moved heightwise of the last.

4. In a toe-lasting machine, means for trimming the margin of one or more inner layers of the toe-end portion of a multi-ply upper on

a last while leaving a margin of the outer layer to be lasted over an insole on the last next to the insole, wipers for wiping the margin of the outer layer inwardly over the insole, a toe former movable heightwise of the last after the upper-trimming operation to conform the toe end of the upper to the contour of the last, said wipers being movable heightwise of the last with the toe former into position for thus wiping the upper inwardly, and means arranged to clamp the margin of the outer layer of the upper on the wipers after the upper-trimming operation and to cooperate with the wipers to apply a pull to that layer only as the wipers are thus moved heightwise of the last with the toe former.

5. In a toe-lasting machine, means for trimming the margin of one or more inner layers of the toe-end portion of a multi-ply upper on a last while leaving a margin of the outer layer to be lasted over an insole on the last next to the insole, wipers arranged to support the margin of the several layers of the upper outspread in the upper-trimming operation and movable thereafter to wipe the margin of the outer layer inwardly over the insole, a toe former for holding the toe end of the upper conformed to the contour of the toe end of the last adjacent to the wipers while its margin is thus trimmed, said toe former and wipers being movable as a unit heightwise of the last after the upper-trimming operation to cause the toe former again to conform the toe end of the upper to the contour of the last, and means arranged to clamp the margin of the outer layer of the upper on the wipers and to cooperate with the wipers to apply a pull to that layer only as the wipers and the toe former are thus moved heightwise of the last.

6. In a toe-lasting machine, means for trimming the margin of one or more inner layers of the toe-end portion of a multi-ply upper on a last while leaving a margin of the outer layer to be lasted over an insole on the last next to the insole, wipers for wiping the margin of the outer layer inwardly over the insole, said wipers being movable heightwise of the last opposite its toe-end face after the upper-trimming operation into position for thus wiping the upper inwardly, a cement-applying device movable heightwise of the last into position to apply cement to the toe end of the shoe, and a retarder movable with said cement-applying device into position to clamp the margin of the outer layer of the upper on the wipers in a plane between the edge of the insole and the top of the toe end of the last and movable with the wipers relatively to the cement-applying device to apply a pull to that layer only as the wipers are thus moved heightwise of the last.

7. In a toe-lasting machine, means for trimming the margin of one or more inner layers of the toe-end portion of a multi-ply upper on a last while leaving a margin of the outer layer to be lasted over an insole on the last next to the insole, means for applying a pull to the margin of the several layers of the toe-end portion of the upper prior to the upper-trimming operation, wipers for wiping the margin of the outer layer inwardly over the insole after the upper-trimming operation, and means arranged to clamp the margin of the outer layer on the wipers after the upper-trimming operation and to cooperate with the wipers to apply a pull heightwise of the last to that layer only prior to the wiping of its margin inwardly over the insole.

8. In a toe-lasting machine, means for trimming the margin of one or more inner layers of the toe-end portion of a multi-ply upper on a last while leaving a margin of the outer layer to be lasted over an insole on the last next to the insole, means for applying a pull to the margin of the several layers of the toe-end portion of the upper prior to the upper-trimming operation, wipers for wiping the margin of the outer layer inwardly over the insole after the upper-trimming operation, said wipers being movable heightwise of the last opposite its toe-end face into position for thus wiping the upper inwardly, and a retarder arranged to clamp the margin of the outer layer of the upper on the wipers in a plane between the edge of the insole and the top of the toe end of the last after the upper-trimming operation and to cooperate with the wipers to apply a pull to that layer only as the wipers are thus moved heightwise of the last.

9. In a toe-lasting machine, means for trimming the margin of one or more inner layers of the toe-end portion of a multi-ply upper on a last while leaving a margin of the outer layer to be lasted over an insole on the last next to the insole, means for applying a pull to the margin of the several layers of the toe-end portion of the upper prior to the upper-trimming operation, wipers for wiping the margin of the outer layer inwardly over the insole after the upper-trimming operation, said wipers being movable heightwise of the last opposite its toe-end face into position for thus wiping the upper inwardly, a cement-applying device movable heightwise of the last into position to apply cement to the toe end of the shoe, and a retarder movable with said cement-applying device into position to clamp the margin of the outer layer of the upper on the wipers opposite the toe-end face of the last, said retarder being movable with the wipers relatively to the cement-applying device to apply a pull to that layer only as the wipers are thus moved heightwise of the last.

10. In a toe-lasting machine, means for trimming the margin of one or more inner layers of the toe-end portion of a multi-ply upper on a last while leaving a margin of the outer layer to be lasted over an insole on the last next to the insole, means for applying a pull to the margin of the several layers of the toe-end portion of the upper prior to the upper-trimming operation, wipers for wiping the margin of the outer layer inwardly over the insole after the upper-trimming operation, a toe former movable heightwise of the last to conform the toe end of the upper to the contour of the last after the upper-trimming operation, said wipers being movable heightwise of the last with the toe former, and means arranged to clamp the margin of the outer layer of the upper on the wipers and to cooperate with the wipers to apply a pull to that layer only as the wipers are thus moved heightwise of the last.

11. In a toe-lasting machine, means for trimming the margin of one or more inner layers of the toe-end portion of a multi-ply upper on a last while leaving a margin of the outer layer to be lasted over an insole on the last next to the insole, means for applying a pull to the margin of the several layers of the toe-end portion of the upper prior to the upper-trimming operation, wipers for wiping the margin of the outer layer inwardly over the insole after the upper-trimming operation, a toe former movable heightwise of the last to conform the toe end of the upper to the contour

of the last prior to the upper-trimming operation and again after that operation, said wipers being movable heightwise of the last with the toe former, and means arranged to clamp the margin of the outer layer of the upper on the wipers after the upper-trimming operation and to cooperate with the wipers to apply a pull to that layer only as the wipers are moved the second time heightwise of the last with the toe former.

12. In a toe-lasting machine, means movable to trim the margin of one or more inner layers of the toe-end portion of a multi-ply upper on a last while leaving a margin of the outer layer to be lasted over an insole on the last next to the insole, wipers for wiping the margin of the outer layer of the upper inwardly over the insole after the upper-trimming operation, grippers arranged to pull the margin of the several layers of the upper outwardly over the wipers preparatory to the upper-trimming operation and to release the upper to make way for the trimming means, and a retarder arranged to clamp the margin of the outer layer of the upper on the wipers opposite the toe-end face of the last after the upper-trimming operation and to cooperate with the wipers to apply a pull heightwise of the last to that layer only prior to the wiping of its margin inwardly over the insole.

13. In a toe-lasting machine, wipers for wiping the margin of the toe end of an upper inwardly over an insole on a last, a retarder for clamping the margin of the upper outspread on said wipers, a support for said retarder, said support and the wipers being relatively movable heightwise of the last while the retarder is in upper-clamping position, and means on said support for controlling the retarder, said controlling means being mounted to swing in response to such relative movement of the support and the wipers and thereby to move the retarder outwardly over the wipers while maintaining it in parallel relation to the wipers.

14. In a toe-lasting machine, wipers for wiping the margin of the toe end of an upper inwardly over an insole on a last, a retarder for clamping the margin of the upper outspread on said wipers, a support for said retarder, said support and the wipers being relatively movable heightwise of the last while the retarder is in upper-clamping position, and parallel links on said support arranged to control the retarder and to move it outwardly over the wipers in response to such relative movement of the support and the wipers.

15. In a toe-lasting machine, wipers for wiping the margin of the toe end of an upper inwardly over an insole on a last, said wipers being movable heightwise of the last before thus wiping the margin of the upper inwardly, a retarder arranged to clamp the margin of the upper outspread on the wipers and to cooperate with them to apply a pull to the upper as the wipers are moved heightwise of the last, and parallel links arranged to support said retarder, said links being inclined in such relation to the wipers as to impart to the retarder an outward wiping movement over the wipers in response to the movement of the wipers heightwise of the last.

16. In a toe-lasting machine, wipers movable to wipe the margin of the toe end of an upper inwardly over an insole on a last, a retarder arranged to engage the toe end of the insole in the path of the wipers and to clamp the margin of the upper against the wipers as they begin to wipe it inwardly over the insole, and a carrier support

ing said retarder and movable to withdraw it from contact with the upper before the margin of the upper is withdrawn from between it and the wipers by movement of the wipers.

17. In a toe-lasting machine, wipers movable to wipe the margin of the toe end of an upper inwardly over an insole on a last, a retarder arranged to engage the toe end of the insole in the path of the wipers and to clamp the margin of the upper against the wipers as they begin to wipe it inwardly over the insole, said retarder being movable heightwise of the last away from the insole in response to the pressure of the margin of the upper thereon, and a carrier supporting said retarder and movable heightwise of the last to withdraw the retarder from contact with the upper before the margin of the upper is withdrawn

from between it and the wipers by the movement of the wipers.

18. In a toe-lasting machine, wipers movable to wipe the margin of the toe end of an upper inwardly over an insole on a last, a retarder arranged to engage the toe end of the insole in the path of the wipers and to clamp the margin of the upper against the wipers as they begin to wipe it inwardly over the insole, another retarder arranged to clamp the margin of the upper outspread on the wipers farther outwardly than said first-named retarder, and a carrier common to both said retarders and movable heightwise of the last to withdraw them from contact with the upper while the margin of the upper is still between them and the wipers.

BERNHARDT JORGENSEN.

CERTIFICATE OF CORRECTION.

Patent No. 2,367,282.

January 16, 1945.

BERNHARDT JORGENSEN.

It is hereby certified that error appears in the printed specification of the above numbered patent requiring correction as follows: Page 1, first column, line 20, for "lengthwise" read --heightwise--; and that the said Letters Patent should be read with this correction therein that the same may conform to the record of the case in the Patent Office.

Signed and sealed this 8th day of May, A. D. 1945.

Leslie Frazer

Acting Commissioner of Patents.
